METERING ROD BIASING SUPPORT

John H. Krein, Florissant, Mo., assignor, by mesne assignments, to ACF Industries, Incorporated, New York, N.Y., a corporation of New Jersey

Application September 30, 1955, Serial No. 537,824

10 Claims. (Cl. 138—46)

This invention relates to a spring clip type of fastener specifically intended for connecting a carburetor metering rod to an actuating link or bar.

It is conventional practice in the carburetor art to meter fuel flow by a stepped or tapered metering rod operating in a calibrated orifice. Since the rod is smaller than the orifice in varying degrees, it has been found necessary (for uniform performance) to maintain the rod against one side of the orifice, so that it always occupies a fixed relation to the orifice, regardless of vertical position. Ordinarily, a spring forces the rod against one side of the orifice as the rod is moved in and out by the throttle or suction motor, or both.

According to the present invention, a novel spring clip, which resiliently attaches to an operating link at one end, has a spring finger engaging the metering rod for urging the same against the orifice wall. The finger, in turn, is apertured medially to form the operating connection between the link and the rod.

Alternative forms of the present invention are shown in the accompanying drawings, in which:

Fig. 1 is a vertical elevational view of a carburetor with parts broken away to show the spring clip connecting the throttle operated link and the metering rod.

Fig. 2 is a perspective view of the spring clip from the front.

Fig. 3 is a similar view from the rear.

Figs. 4 and 5 are views illustrating the manner of installation of the spring clip.

Fig. 6 is a perspective view of a modification of the spring clip on an enlarged scale.

Fig. 7 is another view on an enlarged scale of the spring clip shown in Fig. 6.

Fig. 1 shows a carburetor having a main body portion 1 within which is a mixture conduit containing a throttle mounted on the usual throttle shaft 2. Lever 3 fixed to the throttle shaft has a pin 4 received in the slot 5 of reciprocating throttle link or rod actuating member 6. Extending laterally of the link 6 is an extension 7 with a bottom notch 8, perhaps better shown in Fig. 4.

The spring clip 10, which will be described more in detail hereinafter, straddles the extension 7 and engages the notch 8, and forms the connection between extension 7 and a metering rod 12 received within fuel metering orifice 13 as defined by a generally circular wall 14.

Figs. 2 and 3 illustrate the spring clip 10 on an enlarged scale. In the modification shown in Figs. 2 to 5, the main body 15 has a thumb piece 16 and integrally formed, depending legs 17 and 18 terminating in divergent ends 19 and 20. Intermediate offset portions or shoulders 21 and 22 are located spaced from the ends 19 and 20. Integrally formed with one end of the body 15 is a finger 24 apertured at 25 to receive the bent free end of the metering rod 12. Finger 24 is offset at 26 below the aperture 25.

In operation, aperture 25 is placed over the end of the metering rod 12, as shown in Fig. 4, and then forced downwardly by pressure on the body 15 until the shoul-

2

ders 21 and 22 engage under the lower surface of the notch 8 in the extension 7. The rocking movement during the engagement of the shoulders 21 and 22 tensions finger 24, pressing the offset portion 26 into engagement with one side of the metering rod 12, which causes it to take up a position against one side of the orifice wall 14.

Figs. 6 and 7 show a modified form of spring clip 30 which has a body portion 35 and spring legs 36 and 37 constructed in the same manner as above described. Likewise, the body portion 35 has a downwardly extending finger 34 apertured at 38 to receive the offset end of a metering rod 42. The finger 34 has an integrally formed offset portion 39 forked at 40 to engage the metering rod 42.

In operation, with the metering rod 42 in the orifice, aperture 38 is placed upon one leg of the bent or L-shaped end of the metering rod 42, and then rotated so that the forked end 40 engages the side of the metering rod. The spring clip 35 is then placed on the extension 7 and pushed downwardly so that the legs 36 and 37 engage in the notch 8. When so secured, extension 39 is tensioned, pressing forked end 40 against the side of the metering rod, urging the same against the side of the orifice wall 14, as shown in Fig. 7.

Certain structures have been described herein which will fulfill all the objects of the present invention, but it is contemplated that other modifications will be obvious to those skilled in the art which come within the scope of the invention as defined by the appended claims.

I claim:

1. In a device for controlling fluid flow, a passageway having a fluid metering orifice defined by wall means, a rod movable axially through said orifice to vary the flow of fluid therethrough, a rod actuating means, and means comprising a resilient clip interconnecting said rod actuating means and said rod for common movements and operable to urge said rod against one side of said orifice wall means, said clip member having a body portion securing said clip to said rod actuating means, a finger on said body provided with an aperture receiving said rod, and a resilient portion on said finger engaging one side of said rod.

2. In a device for controlling fluid flow, a passageway having a fluid metering orifice defined by wall means, a rod movable in said orifice to vary the flow of fluid therethrough, a rod actuating means, and means comprising a clip interconnecting said rod actuating means and said rod for common movements and to urge said rod against one side of said orifice wall means, said clip having a first part securing said clip to said rod actuating means, a second part including an aperture receiving said rod, and a third part urging said rod against said orifice wall means.

3. In a device for controlling fluid flow, a passageway having a fluid metering orifice defined by wall means, a rod movable in said orifice to vary the flow of fluid therethrough, a rod actuating means, and means comprising a clip interconnecting said rod actuating means and said rod for common movements and to urge said rod against one side of said orifice wall means, said clip having a first part securing said clip to said rod actuating means, said first part and said rod actuating means having cooperating interlocking means to attach said clip to said rod actuating means, said clip having a second part including an aperture receiving said rod, and a third part of said clip urging said rod against said orifice wall means.

4. In a device for controlling fluid flow, a passageway having a fluid metering orifice defined by wall means, a rod movable in said orifice to vary the flow of fluid therethrough, a rod actuating means, and means comprising a clip interconnecting said rod actuating means

and said rod for common movements and to urge said rod against one side of said orifice wall means, said clip having a first part including a pair of legs forming a U-shaped attaching portion engaging said rod actuating means and securing said clip to said rod actuating means, said clip having a second part including means receiving said rod for cooperating motion between said second part and said rod, and a third part of said clip engaging said rod and urging said rod against said orifice wall means.

5. In a device for controlling fluid flow, a passageway having a fluid metering orifice defined by wall means, a rod movable in said orifice to vary the flow of fluid therethrough, a rod actuating means, and means comprising a clip interconnecting said rod actuating means and said rod for common movements and to urge said rod against one side of said orifice wall means, said clip having a first part including a pair of legs forming a U-shaped attaching portion engaging said rod actuating means and securing said clip to said rod actuating means, at least one of said legs and said rod actuating means having cooperating interlocking means to securely attach said clip to said rod actuating means, said clip having a second part including means receiving said rod for cooperating motion between said second part and said rod, and a third part of said clip engaging said rod and urging said rod against said orifice wall means.

6. In the device of claim 5, said interlocking means comprising a notch means in said rod actuating means and an offset portion on at least one of said legs.

7. In a device for controlling fluid flow, a passageway having a fluid metering orifice defined by wall means, a rod movable in said orifice to vary the flow of fluid therethrough, a rod actuating means having notch means, and means comprising a clip interconnecting said rod actuating means and said rod for common movements and to urge said rod against one side of said orifice wall means, said clip having a resilient first part including a pair of legs forming a U-shaped attaching portion receiving said rod actuating means and clamping said clip to said rod actuating means with portions of said legs received in said notch means in said rod actuating means to securely attach said clip to said rod actuating means, said clip having a second part including an aperture receiving said rod, and a third part of said clip engaging said rod and urging said rod against said orifice wall means.

8. In a device for controlling fluid flow, a passageway having a fluid metering orifice defined by wall means, a rod having a body portion, a portion movable in said

orifice to vary the flow of fluid therethrough, and a portion generally transverse to said body portion, a rod actuating means, and means comprising a clip interconnecting said rod actuating means and the transverse portion 5 of said rod for common movements and to urge said rod against one side of said orifice wall means, said clip having a first part securing said clip to said rod actuating means, said clip having a second part including an aperture receiving said transverse portion of said rod, and a resilient third part of said clip engaging a side of the body portion of said rod at a point spaced from said aperture and resiliently urging said rod against a portion of said orifice wall means.

9. In a device for controlling fluid flow, a passageway

15 having a fluid metering orifice defined by wall means; a rod having a body portion, a portion movable in said orifice to vary the flow of fluid therethrough, and a portion generally transverse to said body portion; a rod actuating means having notch means, and means comprising a 20 resilient clip interconnecting said rod actuating means and the transverse portion of said rod for common movements and to urge said rod against one side of said orifice wall means, said clip having a first part, said first part including a pair of legs forming a U-shaped attaching portion receiving said rod actuating means and clamping said clip to said rod actuating means with portions of said legs received in said notch means in said rod actuating means to securely attach said clip to said rod actuating means, said clip having a second part including an 25 aperture receiving said transverse portion of said rod, and a third part of said clip engaging a side of the body portion of said rod at a point spaced from said aperture to resiliently urge said rod against a portion of said orifice wall means.

30 35 10. A clip comprising a first portion, a pair of legs on said first portion forming therewith a U-shaped member, a second portion transverse of said first portion and having a hole therethrough, and an inclined extension on said second portion angularly arranged with the axis of said hole and having a free end spaced from said aperture on the side of said aperture away from said first portion.
